FIG. 1 is a perspective view of a highway safety reflector
showing my new design;

FIG. 2 is a front side elevation view thereof, the back side
being a mirror image;

FIG. 3 is a right end elevation view thereof, the left end
elevation view thereof being a mirror image;

FIG. 4 is a top plan view thereof; and,

FIG. 5 is a bottom plan view thereof.

The broken line showing of a reflective coating or sheet on
the side of the reflector in FIGS. 1 and 2 is for illustrative
purposes only and forms no part of the claimed design.
